UNITED STATES PATENT OFFICE.

JOHN SHANNON AND JAMES E. WOOD, OF PORTLAND, OREGON.

RAILWAY BLOCK-SIGNAL.

No. 863,102.

Specification of Letters Patent.

Patented Aug. 13, 1907.

Application filed April 11, 1907. Serial No. 367,604.

To all whom it may concern:

Be it known that we, JOHN SHANNON and JAMES E. Wood, citizens of the United States, residing at Portland, in the county of Multnomah and State of Oregon, 5 have invented a new and useful Railway Block-Signal, of which the following is a specification.

This invention has reference to improvements in railway block signals, and its object is to provide a means whereby when a semaphore or target on a line of way 10 is set at "danger" an operating member in the track will be moved into the path of another operating member upon a locomotive engine so that the two members coöperating will cause the air-brakes to be set when the engineman fails to stop on the display of the "danger" 15 signal.

The invention consists essentially of an inclined member in the track, connected to and operated by the target-setting mechanism, and upon the engine there is provided an air pipe coming from the air-brake system, 20 which air pipe carries an air valve so located beneath the engine as to be in the path of a reciprocating member actuated by the inclined member in the roadway when the latter is sufficiently elevated to come into the path of the engine-carried member. The air valve may 25 also have a connection to a point within reach of the engineman so that the air valve may be closed when it is desired to release the brakes in the usual manner.

The invention will be fully understood from the following detailed description taken in connection with 30 the accompanying drawings forming part of this specification, in which,—

Figure 1 is a cross section of a railway track showing so much of the mechanism carried upon the engine as is necessary for the understanding of the invention and 35 also representing a semaphore signal and means for operating the same located alongside of the railway; Fig. 2 is a longitudinal section of a portion of a railway track and of so much of an engine and parts carried thereby as is necessary for the understanding of the 40 present invention; Fig. 3 is a longitudinal section, with parts shown in elevation, of the air valve; and Fig. 4 is a cross section of the structure shown in Fig. 3.

Referring to the drawings, there are shown the rails 1 of an ordinary railway track mounted upon ties 2 in the 45 usual manner. Located about midway between the two rails 1 is a spring member 3 secured at the ends to the two adjacent ties 2, or, if desirable, to ties more remotely located from each other. This member 3 is preferably elastic so as to normally assume the position 50 shown in dotted lines in Fig. 2, but it may be depressed to occupy the position shown in full lines in Fig. 2. For this latter purpose, there is secured to the under-side of the member 3 about midway of its length an eye 4 to which is connected a chain 5 passing down and 55 under a pulley 6 located in a suitable trough 7 extending laterally across the track, and this chain 5 ulti-

mately passes under another pulley 8 located at a switch tower at the proper distance from the track, and from this pulley 8 the chain 5 extends upwardly to an operating lever 9 on one side of the pivot of the latter. 60 While this operating lever is shown as pivoted on the upper end of a post 10, it will be understood that this is simply indicative of a suitable signal tower; and while the connection between the lever 9 and the spring member 3 has been referred to as a chain, it will be 65 understood that it may consist of connected chains and rods or any other system of connection adapted to transmit motion from the lever 9 to the spring member 3.

Attached to the lever 9 on the side of its pivot opposite to that to which the chain 5 is attached, is another connecting chain or similar structure 11 passing down and under a pulley 12, thence under a pulley 13, on a semaphore post 14, from which pulley 13 the connection 11 extends upward to the semaphore arm 15. It will be seen from the connections described that 75 when the lever 9 is moved in one direction the semaphore arm 15 will be dropped from the "danger" position to the "safety" position and at the same time the spring member 3 will be pulled downward at its middle portion until it assumes about the position 80 shown in solid lines in Fig. 2. When the lever 9 is moved in the other direction the semaphore arm or target will be moved to the "danger" position and the spring member 3 will be permitted to assume the position shown in dotted lines in Fig. 2, to which latter 85 position it constantly tends because of its resiliency. In other words, when the semaphore or target 15 is in the danger position the spring member 3 is in its highest position above the level of the track, while when the semaphore or target 15 is in the safety position the 90 spring member 3 is depressed to a considerable extent below the first-mentioned position.

Coming, now, to the parts located on the engine, it will be noted that the engine is represented by the side bars 16 of the engine frame. Extending across 95 these side bars there is an air pipe 17 connected at one end to another pipe 18 coming from the air-brake system. About midway of the length of the pipe 17 there is included a fixed valve member 19 into the threaded ends of which the two sections of the pipe 17, which 100 pipe is divided for the purpose, are screwed. This valve member 19 has an exterior taper 20 to which is fitted a movable valve casing 21, the interior of which latter is suitably tapered to fit the taper 20 of the stationary valve member 19. The valve casing 21 105 is provided with a port 22 and the stationary valve member 19 is provided with a port 23. The construction is such that on rotating the valve member 21 in one direction the two ports 22 and 23 may be brought into coincidence and then the pipe 17 is placed in 110 communication with the external atmosphere, and when the valve member 21 is moved in the other di-

rection the two ports are moved out of coincidence and the communication of the pipe 17 with the external atmosphere is cut off. The smaller end of the fixed member 19 of the valve is externally threaded 5 to receive nuts 24 which serve to maintain the movable member 21 of the valve on the fixed member. The movable member 21 is provided with a radially extending arm 25 and may also have another radially extending arm 26 on the opposite side, which latter arm is connected by a link 27, or, if necessary, a system of links, to a lever 28 within reach of the engine- 10 man.

Securely fast to the engine frame by means of brace rods 29 is a vertically disposed sleeve 30 located below 15 the free end of the arm 25 of the movable member 21 of the valve. Within this sleeve 30 there is a rod 31 having at its lower end a roller 32 and at a point below its upper end a collar 33, the latter acting as a stop to prevent the rod 31 from falling downward out of the 20 sleeve 30.

The normal position of the valve member 21 is such that its arm 25 is in approximately the position shown in solid lines in Fig. 2, and in this position the ports 22 and 23 are out of coincidence. Also, when the 25 valve is in this position the free end of the arm 25 is in contact with or in close relation to the upper end of the rod 31, which in its normal position has its collar 33 in engagement with the upper end of the sleeve 30.

The relation of the parts is such that when they are 30 in the positions just described they are out of the path of the spring member 3 in the roadbed when the latter is in the depressed position shown in full lines in Fig. 2. If, now, the spring member 3 be permitted to assume the position shown in dotted lines in Fig. 2, 35 it will be in the path of the roller 32 and the latter will ride up on said spring member forcing the rod 31 upward through the sleeve 30 and, therefore, moving the arm 25 of the movable valve member to an extent sufficient to bring the ports 22 and 23 into coincidence.

40 This will allow the escape of the air from the air pipe 17 and the brakes will be applied in the usual manner. It will now be seen that if the semaphore or target 45 be set at danger and the engineman fails to observe the signal either through negligence or for any other cause, and therefore passes a danger signal, the air brakes on a train will be at once set so that the train will be brought to a standstill, and the arrangement

is such that the setting of the brakes may be the "emergency" set of the brakes so that the train will be brought to a standstill very quickly.

We claim:—

1. A means for preventing trains from passing block signals comprising an air valve mounted on an engine, an operating arm extending therefrom, a rod supported on said engine for vertical movement and having its upper end in direct operative relation to the valve arm and its lower end in close relation to the roadbed, and an operating member on the roadbed having an inclined face moving into and out of the path of the movable rod.

2. A means for preventing trains from passing block signals comprising an air pipe connected to the air-brake system, a fixed valve member included in said pipe and provided with a side port, a movable valve member carried by the fixed valve member and having a port open to the air and movable into and out of coincidence with the 60 port in the fixed member; an arm fast on said movable member, a vertically movable rod carried by the engine and having its upper end in direct operative relation to the arm on the movable member of the valve and its lower end adjacent to the roadbed, and an inclined member on the roadbed movable into and out of the path of the vertically movable rod.

3. A means for preventing trains from passing block signals comprising an air pipe communicating with the air-brake system on a train, a valve in said air pipe for putting the latter in communication with the atmosphere, an arm on said valve, a vertically movable rod having its upper end in direct operative relation to the arm on the valve and its lower end provided with a roller, a roadbed member composed of a spring having a normal tendency to move into the path of the roller on the rod, and means for moving said spring member out of the path of the rod.

4. A means for preventing trains from passing block signals comprising an air pipe on the engine connected with the air-brake system, a valve in said pipe; an arm projecting from said valve, a vertically movable rod carried by the engine and having its upper end in operative relation to the arm on said valve and its lower end provided with a roller, a roadbed member composed of a spring having a normal tendency to move into the path of said roller, connections between said spring member and an operating lever located adjacent to the roadway, a semaphore signal target, and connections between the operating lever and the semaphore target for moving the latter and the spring member in unison.

In testimony that we claim the foregoing as our own, we have hereto affixed our signatures in the presence of two witnesses.

JOHN SHANNON.
